DESIGN FOR A WAFFLE BAKER

Everett Worthington, Chicago, Ill., and Murray Ireland, St. Paul, Minn., assignors to McGraw Electric Company, Chicago, Ill., a corporation of Delaware

Application October 14, 1935, Serial No. 58,982

Term of patent 7 years

To all whom it may concern:

Be it known that we, Everett Worthington and Murray Ireland, both citizens of the United States, and residents, respectively, of the city of Chicago, county of Cook, State of Illinois, and of the city of St. Paul, county of Ramsey, State of Minnesota, have invented a new, original, and ornamental Design for a Waffle Baker, of which the following is a specification, reference being had to the accompanying drawing, forming part thereof, in which

Fig. 2 is a view in side elevation thereof,
Fig. 3 is a view in front elevation thereof,

Fig. 4 is a fragmentary sectional view through the lower casing, taken on the line 4—4 of Fig. 3,

Fig. 5 is a fragmentary sectional view taken on the line 5—5 of Fig. 1, and

Fig. 6 is a fragmentary sectional view through the upper casing, taken on the line 6—6 of Fig. 1.

We claim:

The ornamental design for a waffle baker as shown and described.

EVERETT WORTHINGTON.
MURRAY IRELAND.
